FRANZ HEINRICH BENNO STELZER, OF DRESDEN, GERMANY, ASSIGNOR TO THE FIRM
JOHANN CARL MULLER, OF DRESDEN, GERMANY

APPARATUS FOR FORMING CIGAR BUNCHES

Application filed March 29, 1928, Serial No. 265,705, and in Germany March 28, 1927.

The invention relates to a device for forming a cigar bunch in a bunching device which is provided with a coiling apron in which the bunch is disposed and in which it is rolled by a roller over a table surface.

The improved method consists in pressing forming members with inclined pressure surfaces against the bunch enclosed in the coiling apron at both sides thereof which forming members at one end of the bunch form the tip of the cigar and at the other end form the head end of the cigar. The support or carrier for these forming members is operated in such manner that at one time the one forming member with its inclined face forms the tip of the cigar, while the other by a smaller pressure forms the head end of the cigar, the reverse process taking place however on the next operation.

In consequence cigar bunches are produced in which in successive bunches the tip is formed at opposite ends which as is well known is necessary for the convenient application of the binder and wrapper.

The support for the forming members which may consist of a rod can either be adjusted to an inclined position which may be altered by the use of suitable actuating means, or the rod may be moved to and fro longitudinally, the one pressure surface of the one forming member being displaced in one direction in such manner as to come more into contact with the bunch than the other and vice versa.

Moreover the invention provides a mechanical control for mechanical operation of the forming members simultaneously with the operation of the support. For this purpose the forming members are formed as nuts on the rod which is arranged as a screw threaded spindle in such manner that by the rotation of the spindle which is provided with right and left hand screw threads the forming members may be moved outwardly or inwardly. The two part screw threaded spindle is provided at its ends with pinions which engage in lateral racks on the table, the teeth of the racks providing sufficient play to allow one end of the spindle to move ahead of the other or lag behind it

in the movement of the spindle supporting member. The supporting member consists of two oppositely controlled rock levers. The rock levers are formed as double armed levers and mounted on the coiling roller supports which act also as pawl carriers for ratchets mounted on the axis of rotation, said ratchets being provided with operating discs for the double armed levers in such manner that on each outward movement of the coiling roller support the corresponding outward swinging movement of the spindle support takes place.

The forming members are thus exactly guided so that the members in consequence of the displacement can exert a gradual pressure on the bunch enclosed in the apron ensuring proper formation of the bunch.

The invention is illustrated in the accompanying drawings in which Figs. 1 and 2 show the device in side elevation in two different operative positions. Figs. 3 and 4 are plan views. Fig. 5 is an elevation seen in the direction of the arrow in Fig. 1.

Figs. 6 and 7 are detail views.

Figs. 8 and 9 show a further embodiment.

Figs. 10-14 illustrate the mode of operating the forming members, Fig. 10 being a plan view or a horizontal cross section of the forming members with the associated parts before the commencement of the forming operation.

Fig. 11 shows the forming members in the position in which the tip of the cigar is located in the former and the forming of the cigar end is just beginning.

Fig. 12 shows the forming members at the conclusion of the forming operation.

Fig. 13 is a side elevation of the bunching device at the commencement of the bunching operation.

Fig. 14 is a side elevation of the bunching device at the conclusion of the bunching operation.

The cigar bunches W are located in the usual apron 1 which is secured at 2 and 3 to a table on the machine frame A. The surface of this table is of arcuate form and forms a guide track for a roller 5 on which the apron 1 is guided. The spindle of the

roller 5 is mounted in the ends 6 of a double armed rock lever 7 arranged laterally of the table 4 which rock lever swings about an axis 8 on the machine frame. The rock lever 7 is formed with a slot 9 in which engages a roller 10' on a crank pin 10 of a crank disc 11, the driving shaft 12 of which is mounted in the machine frame A. The shaft 12 is driven by means of toothed gear-
ing 13 and 14 from the shaft 15.

The free ends of the levers 7 are fitted in brackets 16 in which is mounted a guide roller 17 for the apron. In the brackets 16 are provided guide slots 18 in which is guided a rod 19 which carries two forming blocks 20 for forming the ends of the bunch. These forming blocks 20 may be adjusted on the rod 19 and secured in position by means of screws 21.

With the rod 19 engage bell crank levers 22 which are mounted at the outer ends of the rock lever 7 and rock about pivots 23. The free arms of the bell crank levers 22 carry rollers 24 which track cams 25. The cams 25 are pivoted at 26 to the two longitudinal sides of the table 4 and at 27 are each pivotally connected with a bell crank lever 28 which may rock about pivot 29 on the frame A. The free arms of the bell crank lever 28 engage by means of rollers 30 on the cam grooves 31 of cam discs 32 which are mounted on a common shaft 33. The shaft 33 carries a pinion 34 which meshes with the pinion 14 so that the cam discs 32 are driven by the shaft 15.

In the inoperative position the rock levers 7 are located at the left hand dead centre (not shown), the apron 1 lying in a recess 35 on the table 4 which is of the form of the cigar bunch. The cigar bunch is laid in this recess and on the lever 7 being swung to the right of Figs. 1 and 2 in consequence of the tension on the apron 1 secured at one end to the end of the table is raised by the roller 5 out of the recess and brought on to the guide track on the table 4. The rollers 24 of the bell crank levers 22 first slide on projections 36 on the cams 25; these projections 36 are so formed that the bell crank levers 22 are turned so far to the left that the forming members cannot contact with the cigar bunch.

In accordance with the invention the result is obtained in a simple manner by inclining the rod 19 with the forming blocks 20 so that the inclined surfaces 37 of the forming blocks 20 do not bear uniformly against the bunch, the more inclined forming member 20 pressing against the bunch more than the other.

To attain this result only the cam disc 32 need be so formed that the one cam 25 is raised at a suitable point of time and the other lowered so that the one bell crank

lever 22 is turned to the left and the other turned to the right.

In Fig. 1, for example, the lever 22 is turned to the right so that the forming members 20 adjacent this lever lies with a large part of its inclined face against the bunch and forms a cigar tip while the other forming member only bears slightly on it and forms the head end (see also Fig. 3). In Figs. 2 and 4 the same lever is shown turned to the left so that the tip is formed at the opposite end.

The rod 19 is continuously under the action of two springs 38 which are secured to the rock levers 7 and pull the rod 19 towards the bunch so that the forming members 20 are immediately brought into operative position as soon as the cams 25 assume a corresponding position.

In Figs. 6, 8 and 9 is shown a second embodiment of the invention in which the rod 19 for the forming members 20 is longitudinally movable but is not inclined. The cams 25 are in this case secured to the machine frame as indicated in Fig. 6. By a simple displacement of the rod 19 in the longitudinal direction either one or the other of the forming members 20 is pressed with its inclined surfaces more than the other against the bunch according to the direction in which the rod 19 is moved. Figs. 8 and 9 show the rod 19 at two successive dead centre positions. The tip is in the one case formed at a and the next time on the next bunch at the opposite end b. Longitudinal displacement of the rod 19 can be effected in known manner by a crank, cam disc or the like.

The cigar bunch W is located in the usual apron 1 which is secured in known manner to the ends of the table 4 carried by the machine frame. The surface of the table is of arcuate form and forms a guide track for the roller 5 about which the apron 1 is guided. The spindles of the roller 5 are mounted on the ends 6 of a double armed rock lever 7 arranged laterally of the table 4 which rock lever rocks about a spindle 8 mounted in the machine frame. The rock lever 7 is provided with a longitudinal slot 9 in which engages the crank pin 10 of the crank disc 11 so that on rotation of the crank pin 10 in the direction of the arrow shown in Fig. 13, the two arms 7 arranged to the left and right of the table 4 rock to and fro and thus the roller 5 rolls on the surface of the table 4.

In Figs. 10-14 the forming members 20 co-operate with the bunch enclosed in the apron 1. These forming members each have a freely rotatable forming roller 39 on the spindle 40 mounted in the forming members. The forming rollers 39 are intended for direct engagement with the apron in which the bunch is enclosed. In

addition the forming members 20 are formed as screw threaded nuts. Each nut is mounted on a screw threaded spindle 41 or 41' which is rotatable as a hollow spindle on the axis 42. The two spindles are provided with right and left hand screw threads and carry at their opposite ends pinions 43, 43' whilst the ends of the spindle 42 are mounted in bearing blocks 44 or 44'. Into these bearings extend the ends of a guide rod 45 which is arranged parallel to the axis of the spindle 42 and which is engaged by the forming members 20 with their forked ends 46.

15 The bearing blocks 44, 44' each fit in a recess 47 on the ends of spindle supporting levers 48, 48'. The bearing blocks 44, 44' are adapted to turn in bearings 47 about the vertical pins 49, 49' which are thus at right angles to the longitudinal direction of the spindle 42.

20 The pinions 43, 43' of the screw threaded spindles 41, 41' engage with the racks 50, 50' which are arranged laterally of the apron 1 on the curved surface of the table 4. As the curve formed with the axis 8 as centre and as the arm 7 swinging about the axis 8 carries spindle supports 48, 48', the pinions 43, 43' must roll over the racks 50, 50' when the rock arms 7 perform a swinging movement in the bunching operation. The spindles 41, 41' are thus rotated as a result of which according to the direction of rotation of the rock arms 7 the forming members 20 formed as screw threaded nuts move outwards or inwards.

25 On the axis 8 are rotatably secured two ratchet wheels 51, one on each side of the table 4. Pawls 52 cooperate with the teeth of these ratchet wheels which pawls are free to rotate on the associated rock arm 7 and are pressed by a spring (not shown) against the teeth of the ratchet wheels 51. In addition a safety pawl 53 is provided for each 30 ratchet which in known manner prevents the return movement of the wheel after it is disengaged by the pawl. The ratchet wheels 51 are stationary when the rock arms 7, for the purpose of completing the bunching operation, swing from the position shown in Fig. 13 into the position shown in Fig. 14. On the return movement of the arms 7 the ratchet wheels 51 are entrained and rotated through one division.

35 A controlling disc 54 is rigidly connected with each ratchet wheel. This disc is provided on its periphery with two different groups of controlling teeth in such manner that a projection 55 of one group alternates with a projection 56 of the other group. The projections 55 are formed as teeth with a continuously increasing cam surface 57 which cam surface in the embodiment illustrated is of straight line form. The projections 56 however are provided with a

curved part 58 concentric with the axis of rotation 8 which is transformed later into a gradually increasing curve 59 which is profiled in the embodiment shown as a straight line. 70

The two controlling discs 54 which are mounted opposite one another on the axis 8 are now displaced relatively to one another in such manner that on the one side there is always a tooth of the one group and on the other side a tooth of the other group (as indicated in the dotted lines in Figs. 13 and 14) the ends 60 of the spindle supporting levers 48, 48' which ends are fitted with rollers, co-operate with the projections of the cam disc 54. These double armed levers turn about the pivot 61 on the rock arms 7. Springs 62 ensure that the ends 60 will remain in engagement with the cam discs 54. 80

85 The operation of the device is as follows:

If the bunch is laid in the apron and the rock arms 7 are in the position shown in Fig. 13 then the forming members 20 are 90 in the position shown in Fig. 10.

Now the arms 7 swing in the direction shown by the arrows in Figs. 13 and 14. In this swinging movement the cam discs 54 remain stationary being held by pawls 53. The ends 60 of the double armed lever 48 at one side of the table 4 comes into engagement with the continuously rising curve 57 of the cam 55 producing a corresponding 95 swinging movement of the double armed lever 48. There is thus imparted to the end of the spindle 42 a separate movement which causes this end to approach the bearing of the roller 5. At the same time the end 60 of the double armed lever 48' on the other side of the table 4 comes into contact with the concentric portion 58 of the other cam 56. As a result at the commencement of 100 the swinging movement of the rock arms 7 the double armed lever 48' does not swing and accordingly the other end of the spindle 42 does not approach the bearing of the roller 5. The end of the spindle associated with the pinion 43 thus advances relatively to the other end of the spindle with its pinion 43' while both ends simultaneously move forwards with the rock arms 7, the pinions 48, 48' rolling on the racks 50, 50' and effecting rotation of the spindles 41, 41'. 105

110 This rotation permits the forming members 20 to move outwards, the forming roller 39 however of the one spindle nut pressing against the end of the bunch and thereby initiating the formation of the tip of the cigar while the forming roller 39 of the other spindle nut does not exert any particular pressure on the bunch at the other end (see the position shown in Fig. 11). 115

120 On further movement of the arms 7 the 130

end 60 of the double armed lever 48' moves over the curve 59 of the corresponding cam 56 whereby the double armed lever 48' is caused to swing so that the spindle end carrying the pinion 43' also approaches the bearing of the roller 5 and on further outward movement of the corresponding forming member 20 the forming roller 39 forms the end of the cigar on the bunch (see the 10 position shown in Fig. 12).

It is to be noted that the racks 50, 50' with the teeth of the pinions 43, 43' provide a sufficient amount of play so that the comparatively small inclination of the spindle 15 42 does not cause jamming of the teeth.

After the position shown in Figs. 12 and 14 is attained the arms 7 move backwards. The ratchet wheels 51 are turned so that now the toothed groups of the cam discs 20 at the two sides of the device are reversed. Now, when the next succeeding operative movement of arm 7 takes place, a cigar tip will be formed on the bunch being rolled, at the opposite end of said bunch to that 25 formed on the preceding bunch, and similarly a head end would be formed on the other end of said bunch. Thus at the conclusion of this next succeeding operative movement of arm 7, the representation of 30 Fig. 14 would be reversed, i. e. the head end of the cigar would be at the left and the tip end at the right. A plurality of rolled cigar bunches arranged consecutively as they come off the forming machine would 35 exhibit alternate heads and tips on the right and left respectively.

I claim:

1. Means for bunching cigars including in combination with a table a bunching apron and a bunching roller serving to move said bunching apron over said table, forming members, a support for said forming members and means for actuating said support whereby to form the tip and head on one bunch at one end and the tip and head at the reverse end on the succeeding bunch. 45

2. Means for bunching cigars including in combination with a table, a bunching apron and a bunching roller serving to move said bunching apron over said table, forming members, said forming members movable relatively to one another and means including cams for actuating said forming members whereby to produce differential movement of said forming members, substantially as and for the purpose set forth. 50

3. Means for bunching cigars including in combination with a table, a bunching apron and a bunching roller serving to move said bunching apron over said table, forming members, said forming members movable relatively to one another, means including cams for actuating said forming members whereby to produce differential movement 65 of said forming members, said cams ar-

ranged on rock levers said rock levers pivotally mounted on said table and levers acting on the free ends of said rock levers, said last mentioned levers also being actuated by cams, substantially as and for the purpose set forth. 70

4. Means for bunching cigars including in combination with a table a bunching apron and a bunching roller serving to move said bunching apron over said table, forming members, and a rod supporting said forming members, said members having pressing surfaces, said surfaces longitudinally movable and arranged to act differentially on the bunch, substantially as and for the purpose 75 80 set forth.

5. Means for bunching cigars including in combination with a table, a bunching apron and a bunching roller serving to move said bunching apron over said table, forming members, and a rod supporting said forming members, said rod formed as a screw threaded spindle with threads of opposite hand and said forming members arranged as nuts on said rod, substantially as and for the 85 90 purpose set forth.

6. Means for bunching cigars including in combination with a table, a bunching apron and a bunching roller serving to move said bunching apron over said table, forming members, a rod supporting said forming members, said rod formed as a screw threaded spindle with threads of opposite hand and said forming members arranged as nuts on said spindle, said spindle fitted with pinions and lateral racks loosely engageable by said pinions, substantially as and for the 95 100 purpose set forth.

7. Means for bunching cigars including in combination with a table, a bunching apron and a bunching roller serving to move said bunching apron over said table, forming members, a rod supporting said forming members, said rod formed as a screw threaded spindle with threads of opposite hand and supports for said spindle, said supports consisting of rock levers. 105 110

8. Means for bunching cigars including in combination with a table, a bunching apron and a bunching roller serving to move said bunching apron over said table, supports for said bunching roller, forming members, a rod supporting said forming members, said rod formed as a screw threaded spindle with threads of opposite hand and supports for said spindle, said supports consisting of rock levers, said rock levers formed as double armed levers and mounted on said bunching roller supports, said supports carrying pawls, ratchets engageable by said pawls and cams formed on said ratchets, said cams adapted to co-operate with said double armed levers, substantially as and for the purpose 115 120 125 set forth.

9. Means for bunching cigars including in 130

combination with a table, a bunching apron and a bunching roller serving to move said bunching apron over said table, supports for said bunching roller, forming members, a rod supporting said forming members, said rod formed as a screw threaded spindle with threads of opposite hand and supports for said spindle, said supports consisting of rock levers, said rock levers formed as double armed levers and mounted on said bunching roller supports, said supports carrying pawls, ratchets engageable by said pawls and cams formed on said ratchets, said cams adapted to co-operate with said double armed levers, said cams provided with two different groups of projections, substantially as and for the purpose set forth.

10. Means for bunching cigars including in combination with a table, a bunching apron and means for moving said bunching apron over said table, forming members, said forming members movable relative to one another and means for actuating said forming members to produce differential movement of the same.

11. In a cigar bunching machine, means for bunching cigars including in combination with a bunching table, a bunching apron, means for moving said bunching apron over said table, forming means, means for actuating said forming means to produce differential movement thereof and means for causing said forming means to produce a head and tip on the ends of one cigar bunch and a head and tip in reverse manner on the next succeeding cigar bunch.

12. In a cigar bunching machine, means for bunching cigars including a bunching apron, means for actuating said apron, means for forming cigar bunches in said apron and means actuating said forming means whereby a head and tip are formed on the ends of one cigar bunch and a head and tip in reverse manner are formed on the next succeeding bunch.

In testimony whereof I affix my signature.
FRANZ HEINRICH BENNO STELZER.
